United States Patent Office

Des. 184,962
Patented Apr. 21, 1959

184,962

TRASH CAN CART

Charles Ress, Youngstown, Ohio

Application April 11, 1958, Serial No. 50,438

Term of patent 3½ years

(Cl. D14—3)

The figure is a perspective view of a trash can cart, showing my new design.

I claim:

The ornamental design for a trash can cart, as shown.
